CLOTHESPIN

Junie Etta Sprague, Los Angeles, Calif.

Application November 26, 1940, Serial No. 367,181

2 Claims. (Cl. 24—137)

This invention relates generally to fastening devices and particularly to a clothespin.

The main object of this invention is to produce an improved form of clothespin which will be inexpensive to manufacture, not subject to breakage and easy to apply to the garment and supporting line.

The second object is to so construct a clothespin, of the type described, in a manner that it may easily attach to a line and if desired permit it to slide along said line.

The third object is to construct a clothespin of the class described in a manner to adapt itself to the use of plastic materials and in which the amount of material employed is reduced to a minimum.

The fourth object is to construct a clothespin of the class described employing a flat wire spring which is assembled with the clamping members by a lateral movement of the spring, that is in parallelism with the hinge axis of the clothespin.

The fifth object is to construct a clothespin in a manner that it will not become stained or discolored in use and that it will not impart such stains to the garments being supported thereby.

The sixth object is to construct a clothespin in which the line cannot become fouled with the spring.

I accomplish these and other objects in the manner set forth in the following specification as illustrated in the accompanying drawing, in which:

Fig. 1 is a side elevation of the device showing the supporting line and the supported fabric in cross section.

Fig. 2 is a plan of the device showing same mounted on a clothesline.

Fig. 3 is the front elevation of the clothespin in a clothes supporting position.

Fig. 4 is a side elevation of the clothespin showing the manner of operating the same.

Fig. 5 is a side elevation of the clothespin showing the same suspended from a hook.

Fig. 6 is a section taken along the line 6—6 in Fig. 1.

Similar numerals refer to similar parts throughout the several views.

Referring in detail to the drawing, there is shown a pair of elongated arms 10 having the semicircular openings 11 formed near the jaw end 12 and also having the smaller grooves 13 formed between the opening 11 and the central portion 14. The end 15 of each arm 10 is pro-

vided with a hole 16 by means of which the pin may be suspended from a hook 17.

Referring to the spring element itself, this is preferably in the form of a U shaped flat spring 18 having the rounded closed end 19 and the channel shaped open ends 20 which fit into corresponding slots in the members 10. While the manner of attaching the straight sides 21 of the spring 18 to the members 10 is of lesser importance, it is desirable to do so in the manner indicated as it lends itself to the production of the device from molded plastic material.

It must be understood that while in Fig. 1, I have shown the fabric 22 as being held only between the jaws 12 while the spring end 19 engages the clothesline 23, in actual practice the fabric 22 would occupy the openings 11 in the same manner that devices of this kind are now employed.

20 It will also be understood that in some instances it may be found desirable to flare the outer end of the jaws 12 outwardly to facilitate the placing of the clothespin on a garment which is supported on the clothesline.

25 The use of the clothespin is so well understood that it will not be repeated here, the present invention being directed toward the production of a clothespin having the advantage of the well known devices of this type without possessing their disadvantages.

30 It will be seen that in Fig. 5 the ends 24 are turned away from the ends 16. As stated the precise form of the spring end is unimportant.

35 While I have suggested the desirability of plastic material in the making of these pins, it must be understood that if plastic is used it must be of a type that will withstand a considerable amount of heat in order to avoid the distortion thereof in warm climates. A popular material 40 for making these devices is one of the semihard tough woods such as birch.

45 While I have thus illustrated and described my invention, it is not my intention to be limited by this precise form shown therein but I intend to cover all such forms and modifications of my invention as fall fairly within the appended claims.

I claim:

1. A clothespin of the class described consisting of a pair of elongated arms of plastic material converging at one end to form a pair of clothes engaging jaws, and diverging at the opposite end to form operating handles, a U shaped spring of flat wire disposed between said arms 50 having the open ends of said spring outwardly

and backwardly turned toward the closed end thereof, said backwardly turned ends being imbedded in the clothes engaging end of the arms, each of said arms having a median point fulcrumed on a median point of its adjacent spring side.

2. A clothespin of the class described consisting of a pair of elongated arms of plastic material having their greatest thickness near the middle of their length, one pair of arm ends con-

stituting handles and the other pair of arm ends constituting clothes engaging jaws, a U shaped spring of flat wire having its closed end disposed between the handle members and its open end 5 backwardly turned and imbedded in the clothes engaging end of the arms, the sides of said spring being outwardly turned and forming fulcrum points for the thick portions of said arms.
